(57) CLAIM

I claim the ornamental design for a barbecue grill, as shown and described.

DESCRIPTION

FIG. 1 is a front perspective view of a barbecue grill in accordance with the new design.

FIG. 2 is a front elevational view of the barbecue grill of FIG. 1.

FIG. 3 is a back elevational view of the barbecue grill of FIG. 1.

FIG. 4 is a right side elevational view of the barbecue grill of FIG. 1.

FIG. 5 is a left side elevational view of the barbecue grill of FIG. 1.

FIG. 6 is a top plan view of the barbecue grill of FIG. 1; and, FIG. 7 is a bottom plan view of the barbecue grill of FIG. 1.

The dashed lines are for illustrative purposes only and form no part of the claimed design.
